Ned F. Nickles, Detroit, Mich., assignor to General Motors Corporation, Detroit, Mich., a corporation of Delaware

Application February 3, 1950, Serial No. 7,717

Term of patent 7 years

(Cl. D14—18)

To all whom it may concern:

Be it known that I, Ned F. Nickles, a citizen of the United States, being a resident of Detroit, State of Michigan, have invented a new, original, and ornamental Design for an Automotive Vehicle Hood Ornament, of which the following is a specification, reference being made to the accompanying drawing, forming a part thereof.

In the drawing:

Figure 1 is a plan view of an automotive vehicle hood ornament, showing my new design.

Figure 2 is a side elevational view thereof.

Figure 3 is an end elevational view thereof.

Figure 4 is a sectional view taken substantially on line 4—4 of Figure 1.

I claim:

The ornamental design for an automotive vehicle hood ornament, substantially as shown.

NED F. NICKLES.
